(57) **CLAIM**

We claim the ornamental design for an USB drive, as shown
and described.

DESCRIPTION

FIG. 1 is a perspective view of an USB drive showing our new
design:

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

1 Claim, 4 Drawing Sheets
